UNITED STATES PATENT OFFICE.

JOSEPH O'NEIL, OF TAYLORSTOWN, PENNSYLVANIA, ASSIGNOR OF TWO-
THIRDS TO FRANK L. MASSON, OF SAME PLACE, AND CHARLES C.
CHAMBERLIN, OF WASHINGTON, PENNSYLVANIA.

PUMP.

SPECIFICATION forming part of Letters Patent No. 651,314, dated June 5, 1900.

Application filed February 23, 1897. Serial No. 624,558. (No model.)

To all whom it may concern:

Be it known that I, JOSEPH O'NEIL, a citizen of the United States, residing at Taylors-
town, in the county of Washington and State
5 of Pennsylvania, have invented or discovered
new and useful Improvements in Pumps, of
which the following is a specification.

In the accompanying drawings, which make
part of this specification, Figure 1 is a ver-
10 tical elevation of my improved pump and the
inclosed cage and cups beneath the same.
Fig. 2 is a vertical section of Fig. 1. Fig. 3
is a plan of a sleeve secured on the upper end
15 of the stationary stand-pipe. Fig. 4 is a side
elevation of the upper end of the stand-pipe
and sleeve. Fig. 5 is a vertical section through
the pump-seat and the adjacent tubing, show-
ing the cups on the valve-body, the inclosed
20 cage, and the stuffing-box broken off of the
pump-valve.

The purposes of my invention, generally
stated, are to devise an inexpensive form of
pump which shall do away with the ordinary
working barrel and also with a plunger pro-
25 vided with cups. A further purpose is to
make the pump self-lifting to a given degree,
thereby greatly reducing the strain on the
sucker-rods and enabling me to use a lighter
form of such rods.

30 It is well known to those skilled in the art
that the working barrels of the ordinary pump
are by far the most expensive portion there-
of. They require to be machined with the
greatest accuracy and must be carefully pol-
35 ished internally to accurately fit the plunger.
It is further familiar to those acquainted with
the art that the cups on the plungers are a
source of constant annoyance and delay and
expense, particularly in wells containing
40 floating sand, since such cups will be cut and
require frequent renewal.

In the present invention I have no working
barrels nor any reciprocating plunger nor any
45 cups to form a packing between said working
barrel and plunger; as will be more clearly
brought out below.

In the accompanying drawings, which make
part of this specification, 2 is the ordinary
standing valve-body, provided with the cups

a a and having the usual longitudinal perfor- 50
ation b. To the upper end of said valve-
body is screwed any well-known form of cage
3, provided with ball-valve 4, seated upon the
valve-seat 5, the throw of said ball-valve be-
ing limited by the inwardly-projecting lugs 55
3^a. The parts thus far mentioned are old in
the art.

I now come to those parts which I claim
to be distinctively new, in themselves and
new in combination with the parts just de- 60
scribed.

6 is a hollow stand-pipe secured to the up-
per end of cage 3 and like it remaining sta-
tionary in the well, except when withdrawn
for repairs, &c. The bore of this hollow 65
stand-pipe connects with the bore of the cage
and valve-body. The hollow stand-pipe 6 is
provided at its upper end with a sleeve 7, hav-
ing longitudinal passages 7^a. The sleeve 7
does not act as a plunger, for it remains sta- 70
tionary and only loosely fits in the shell to be
described.

8 is a reciprocating shell which moves upon
the stationary stand-pipe 6 as a guide, and a
close joint between the two is secured by 75
means of the stuffing-box 9, gland 10, follower
11, and packing 12. To the upper end of said
reciprocating shell is secured the ordinary
subpiece 13, on which rests the valve-seat 14,
supporting ball-valve 15 in open cage 16, 80
screwed to subpiece 13. To the upper end of
cage 16 are secured in the usual manner the
sucker-rods.

As shown in Fig. 5, 17 is the pump-seat,
which incloses the valve-body and closed cage, 85
said pump-seat 17 being interposed between
and screwed to two sections of tubing 18 and
18. This is a construction which I prefer for
the pump-seat when the pump is put into a
well with the tubing; but in cases where the 90
tubing is already in and it is not desirable to
remove the tubing from the well to insert the
pump-seat my pump can be set on top of the
working barrel already in the well, and thus
obviate the necessity of drawing the tubing. 95

The operation of the pump is as follows:
When the sucker-rods are lifted, the shell 8
will rise, being guided in its movement by a

rubbing contact between its stuffing-box and the vertical stand-pipe 6. The displacement of the oil occasioned by the upward movement of the shell 8 will cause an inrush of 5 the oil through the passage *b*, raising the ball-valve 4, and through the vertical stand-pipe 6 into the interior of the shell 8. In the meantime the oil which has previously been caught 10 between the under side of the sleeve 7 and the upper side of the gland 9 will escape as these parts approach each other through the channel 7^a 7^a into the upper part of the shell 8. On the downward movement of the sucker-rod the shell 8 would be depressed, the ball 4 15 will seat itself, and the oil in the shell 8 will pass up through the subpiece 13 and raise the ball 15 and so pass up the well. It will be further observed that owing to the difference in area between the sleeve on the upper end 20 of the stand-pipe 6 and the stuffing-box at the bottom of shell 8, the well-pressure in an upward direction against the under side of said stuffing-box will be exerted on a greater cross-section than the well-pressure in a downward direction upon the upper side of the 25 sleeve. Hence the well-pressure upwardly will overbalance to a certain extent the well-pressure exerted downwardly and will tend to this extent to help raise the sucker-rods. 30 This is directly contrary to the ordinary operation of the usual pump, since in lifting the ordinary pump not only lifts the weight of the sucker-rods, but must also lift the weight of the fluid in the well above. 35 It should be further noted that the only packing used between the moving and the stationary parts of the pump is an ordinary packing 6^a, which is well-nigh inaccessible to the sand and which cannot be so easily cut as the old-style cups. This packing fits around the stand-pipe 6 and obviates the necessity of a carefully-bored and polished working barrel. The construction is therefore cheap, simple, and not requiring such frequent renewals. 40 45 The shell 8 is only an ordinary tube, requiring no special machining or fitting.

The function of the sleeve 7, as heretofore stated, is not to act as a piston or plunger, but it merely acts as a collar to lock against the upper end of the gland 9 when it is desired to draw the entire apparatus from the well.

Various changes may be made in the de-

tails of construction and fitting together of the parts while still retaining the broad features of my invention, and I do not wish to 55 limit myself by implication to any special restricted features of construction unless such features are expressly enumerated in the claims.

Having described my invention, I claim— 60

1. In pumps, the combination of a stand-pipe fixed in the well; tubing for said well; a tube within the tubing adapted to reciprocate upon said pipe; sucker-rods from which said tube is suspended and a stuffing-box carried by the reciprocating tube and interposed between said tube and said stand-pipe. 65

2. In pumps, the combination of a stand-pipe fixed in the well; a collar having fluid-passages on the upper end of said stand-pipe; 70 tubing for said well; a tube within the tubing adapted to reciprocate upon said stand-pipe; sucker-rods from which said tube is suspended and a stuffing-box interposed between said stand-pipe and the lower end of said reciprocating tube. 75

3. In pumps, the combination of a stand-pipe fixed in the well; tubing for said well; a tube within the tubing adapted to reciprocate upon said stand-pipe; the annulus of said 80 tube having a greater cross-sectional area than the cross-sectional area of the stand-pipe; sucker-rods from which said tube is suspended and a stuffing-box interposed between said stand-pipe and the lower end of said reciprocating tube. 85

4. In pumps, the combination of tubing; a pump-seat interposed between and secured to two sections of the tubing; a valve-cage supported upon said pump-seat; a stand-pipe secured to said valve-cage; a tube suspended within the tubing from the sucker-rods and adapted to reciprocate upon said stand-pipe; 90 said sucker-rods; and a stuffing-box with ordinary packing interposed between said stand-pipe and the lower end of said reciprocating tube. 95

In testimony whereof I have hereunto set my hand this 16th day of February, A. D. 1897.

JOSEPH O'NEIL.
